192,757

CLOSURE OR SIMILAR ARTICLE

George J. Foss and Daniel D. Acton, Lancaster, Ohio, assignors to Anchor Hocking Glass Corporation, Lancaster, Ohio, a corporation of Delaware

Filed Nov. 16, 1960, Ser. No. 62,863

Term of patent 14 years

(Cl. D58—26)

FIG. 1 is a perspective view of a closure or similar article, showing our new design;

FIG. 2 is a top plan view thereof;

FIG. 3 is a bottom plan view thereof;

FIG. 4 is a side elevational view thereof;

FIG. 5 is an enlarged sectional view taken along line 5—5 of FIG. 2; and

FIG. 6 is an enlarged sectional view taken along line 6—6 of FIG. 2.

We claim:

The ornamental design for a closure or similar article, substantially as shown.
